LUMINAIRE REFRACTOR

Vearl S. Wince, Newark, Ohio, assignor to Holophane
Company, Inc., New York, N.Y., a corporation of
Delaware

Filed May 7, 1965, Ser. No. 85,182

Term of patent 14 years

(Cl. D48—16)

Fig. 1.

Fig. 2.

FIG. 3

FIG. 4

FIG. 5

FIG. 1 is a perspective view of a luminaire refractor showing my new design;

FIG. 2 is a section taken along line 2-2 of FIG. 1;

FIG. 3 is a top plan view thereof;

FIG. 4 is a bottom plan view thereof; and

FIG. 5 is a side elevation view thereof.

The central portion of the luminaire refractor has been shown broken away in FIGS. 1, 3, 4 and 5, for convenience of illustration and to indicate indeterminate length. The prism pattern is understood to be continuous throughout the length of the refractor.

I claim:

The ornamental design for a luminaire refractor, substantially as shown and described.
